COMBINED HOOD AND RESPIRATOR

George H. Schauweker, Southbridge, Mass., assignor to American Optical Company, Southbridge, Mass., a voluntary association of Massachusetts

Application November 19, 1947, Serial No. 786,914

14 Claims. (Cl. 128—141)

1

This invention relates to a combined hood and respirator and has particular reference to hoods adaptable for attachment to respirators and having transparent windows located therein.

It is common practice in this field to provide respirators with face shields and hoods. However, it is uncommon to find combined hoods and respirators wherein the hoods may be interchangeable with a number of respirators and have means for removably securing in the front portions thereof transparent eye shields or windows.

Therefore, it is an important object of this invention to provide an improved head protecting hood adaptable for and interchangeable with various types of respirators.

Another object is the provision of means in the hood for the removable securement of transparent eye shields or windows.

Another object is the provision of a hood shaped to cover the entire head of a wearer and extending downwardly to drape over the wearer's shoulders and having means for easily securing the hood to and detaching it from a respirator.

Other objects of the invention are to provide a hood of such construction as to give maximum protection to the head of the wearer, to provide inconspicuous and secure attachment of the hood to a respirator and of a window to the hood, and to provide a hood of light weight and neat appearance.

Further objects are to provide in a manner as hereinafter set forth a hood adapted for attachment to a respirator which is simple in its construction, durable, thoroughly efficient in its use, readily attachable and detachable, and comparatively economical to manufacture.

Other objects and advantages of the invention will become apparent from the following description taken in connection with the accompanying drawings, in which:

Fig. 1 is a perspective view of a combined hood and respirator embodying the present invention;

Fig. 2 is a sectional view taken substantially on line 2—2 of Fig. 1;

Fig. 3 is a sectional view taken on line 3—3 of Fig. 1;

Fig. 4 is a sectional view taken on line 4—4 of Fig. 1;

Fig. 5 is a sectional view taken on line 5—5 of Fig. 4;

Fig. 6 is a vertical section taken through the fastening means to close the opening in the front of the hood;

Fig. 7 is a fragmentary front elevation of a

2

preferred type of window mounted in the front of the hood; and

Figs. 8 and 9 are fragmentary front elevations of modified types of windows for the hood.

Referring more particularly to the drawings wherein like characters of reference designate like characters throughout the several views, the device embodying the invention comprises broadly a hood 10 attached to a respirator 11, the respirator including a face piece 12 shaped to snugly fit over the lower portions of the wearer's face, covering entirely the nose and mouth, and being held securely in position by a headband 13 connected to opposite sides of the face piece 12 and adapted to extend around the wearer's head.

The usual inhalation means is provided on the face piece 12 in the nasal region thereof and is illustrated as a cylindrical filter cartridge 14 attached by suitable means to a plate-like supporting member 15 located on the front of the face piece 12. The usual exhalation means is provided adjacent the mouth of the wearer and is shown as a depending tubular member 16 on the face piece 12. The walls of the face piece 12 are pliable and shaped to conform generally to the shape of the wearer's face and when drawn snugly thereagainst by tightening the straps 13 the edges thereof provide an air tight seal therearound. This will prevent foul air, gases or the like from reaching the respiratory tract of the wearer.

The respirator alone however does not protect the head of the wearer from foreign materials such as emery dust, sand or bits of metal which may be present in the air and which might cause injury to the face and particularly to the eyes of the wearer. Therefore a hood 10 is provided for attachment to the respirator and may be made of any suitable fabric such as nylon, silk, canvas, or the like and may be chemically treated for waterproofing if desired. The hood 10 comprises a cap portion 17 having a substantially disc-shaped top portion 18 with a depending marginal strip 19 stitched thereto and a visor 20 attached on the front thereof. The cap portion 17 is provided with an interior perspiration absorbing liner 21 shaped substantially to the shape of the cap portion 17 and having a depending marginal portion 22 stitched along its lower edge to the outer portion 19, the lining 21 having a rear cut out section 23 the ends of which are joined by an elastic band 24 (Fig. 4), the band being stitched or otherwise secured at each end to the marginal portion 22 of the liner and being provided as a

means for fitting the hood to various shapes and sizes of heads.

The visor 20 has a stiffener 25 formed of leather or the like located between the upper and lower coverings 26 and 27 respectively (Fig. 3), the upper covering 26 being secured at one end to the cap portion 19 and at its other end to one end of the lower covering 27 which in turn is connected at its other end to the liner 22.

The remainder of the fabric hood 10 is formed in three sections, two portions 28 and 29 forming a front panel, and a rear panel 30, the frontal portions being stitched together or otherwise connected centrally of the hood below the visor 20 and adapted to drape downwardly, each having an eye 31 located in its lower regions. The frontal portions 28 and 29 are secured at their upper ends to the cap portion 17 and may for strength have a reinforcing strap 32 located integral with this seam. The portions 28 and 29 extend slightly rearwardly and are connected to the rear panel 30 as indicated in Fig. 1, the rear panel 30 also being connected at its upper end to the cap portion 17, and being adapted to drape downwardly to a point below the shoulders of the wearer. Thus, there is formed a hood completely covering the head of the wearer, the sides of the hood near the seams formed by connecting the frontal portions 28 and 29 to the rear panel 30 having cut out portions to adapt the hood to properly fit over the shoulders of the wearer, and thereby providing downwardly draped coverings for the upper chest and back of the wearer.

A strap 33 formed of any suitable material is secured to the lower end of the rear portion 30, the strap having ends adapted to extend under the arms of the wearer and to be tied to the eyes 31 located in the frontal portions 28 and 29. Thus, the hood may be securely and snugly held in place.

The upper end of the panel formed by joining the frontal portions 28 and 29 has a cut out portion immediately below the visor 20. This cut out portion has a marginal reinforcement or frame 34 bordering the sides and lower edge thereof formed of leather or the like and secured by stitches or other suitable means to the panel (Fig. 7), the frame 34 being substantially U-shaped in section to form a bezel adapted to receive a window or eye shield 35 formed of transparent flexible sheet material such as synthetic plastic or the like, the window being adapted to be inserted from the top of the cut out portion and slid downwardly within the bezel or frame 34, and having been previously shaped to the contour of the cut out portion. Lateral strips 36 and 37 abut the upper edge of the window on the front and rear sides respectively (Fig. 3) and are connected to the upper ends of the frame 34. The front strip 36 is provided with a number of connection members 38 which are adapted to cooperate with other connection members 39 secured to a flap 40, the flap being secured by stitches or the like to a lateral tab 41 secured to the under side of the visor 20. Thus the window 35 may be mounted in the frame 34 between the lateral strips 36 and 37, and the flap 40 may be brought into overlapping relation with the upper edge of the window 35 and frame 34 whereby the connection members 38 and 39 may be fastened to secure the flap in position for sealing the entrance to the frame 34 and retaining the window 35 in place.

It is to be understood however that the window 35 may be of various types, sizes and shapes

and may be formed of two separate panes 42 (Fig. 8) with a frame 43 having a vertical centrally located strip 44 between the panes 42, with entrances being provided at the outer sides of the frame with flaps 57 covering the entrances in a manner similar to the flap 40 in Fig. 7. Also, it may be desired to have the window 35 shaped to desired size and permanently secured to the hood 10 as shown in Fig. 9, wherein the window 35 is secured directly to the hood by stitching, gluing or the like without the provision of a frame. However, the latter type of window has the disadvantage of being permanently mounted in the hood and not removable and interchangeable as is the preferred type shown in Fig. 7.

Centrally located near the lower edge of the window 35 is an opening 45 and a pair of downwardly extending convergent straps 46 formed integral with the lower edge of the frame 34 having their ends spaced below the opening 45 in a manner such as to provide a passageway into the opening. One of the straps 46 is provided near the end thereof with a male clip portion 47 of a snap fastener adapted to be connected with a female portion 48 carried by the other strap 46. Other means however may be utilized to connect the ends of the straps 46 in overlapping relation.

The adjacent edges of the frontal portions 28 and 29 of the hood 10 immediately below the straps 46 and opening 45 are left free and are not stitched together as is the remaining portions of the edges as indicated by seam 49. The free edges are adapted to overlap and are connected by a snap fastener arrangement shown to best advantage in Figs. 6 and 8. Located near the free edge of frontal portion 29 is a male clip portion 50 of the snap fastener which is adapted to be connected with a female portion 51 carried by the adjacent free edge of frontal portion 28. Minute details of the snap fastener are not deemed necessary in this specification since many suitable types of snap fasteners are available which are adaptable to this invention. Therefore it is believed advisable only to relate briefly that as shown in Fig. 6 the female portion 51 of the fastener has an internal flange member 52 adapted to secure the edge of the frontal portion 28 between the main member 51 and said flange member 52 with a piece of fabric material or the like 53 secured to the portion 28 for reinforcement purposes. The male portion 50 is secured in position on the edge of frontal portion 29 by means of a washer-like member 54 and an internal flange portion 55 between which the portion 29 and its corresponding reinforcement 56 are secured. This type of fastening means may be used for securing the flaps 40 and 44 and connecting the strap members 46.

A pair of spaced openings are provided at each side of the hood 10 near the forward edges of the rear panel 30 through which the headband 13 of the respirator 11 may extend as shown in Fig. 1, this being done to provide means for externally adjusting the headband 13 on the wearer's head after the hood has been secured to the respirator as well as to eliminate excess looseness in the fit of the hood 10 around the wearer's head.

In positioning the hood on a respirator, the front portion of the hood is located over the front of the respirator with the window 35 being positioned between the face piece 12 and the cartridge supporting member 15. To attach the hood to the respirator the straps 46 are spread and the hood pulled down over the top of the

respirator with the connecting member between the cartridge supporting member 15 and face piece 12 being positioned in the opening 45 below the window 35, and the straps 46 extending below the face piece 12 and into the space between the lower contour edge of the member 15 and the front of the depending tubular exhalation valve carrying member 16. With the hood in this position the straps 46 can be drawn together and the snap fastener closed to seal the opening 45 so that the hood cannot become displaced.

Also drawing together the straps 46 will cause the front of the window to bend and assume a cup-like convex shape, covering the face of the wearer. The opening formed at the upper end of seam 49 between the free ends of frontal portions 28 and 29 of the hood 10 is provided so that the depending tubular exhalation valve carrying member 16 may be permitted to project outwardly below the straps 46, with the free ends carrying snap fastener portions 50 and 51 being adapted to be drawn into lapping relation below the member 16 so that the fastener parts 50 and 51 may be closed to seal the hood beneath the member 16.

When it is desired to substitute one hood for another or to change a hood from one respirator to another respirator the straps 46 and snap fastener parts 50 and 51 are disconnected and the straps 46 drawn away from one another to open the passageway into the opening 45, and the hood may then be pulled upwardly to disconnect it from the respirator. When a window 35 has become scratched, pitted or otherwise defective it can be easily withdrawn from the frame 34 after opening the flap 40, and a replacement window easily inserted in its place.

Thus from the foregoing description it can be understood that a hood of this type can be very economically made and efficient in its use and can also be readily attached, removed and replaced. It is quite apparent that when the hood is applied to a respirator in a manner as hereinbefore described no harmful material can gain access to the head of the wearer. By virtue of the elastic band 24 the hood can be adapted to fit various sizes and shapes of heads thereby eliminating the necessity of providing a number of hoods of different sizes. The snap fastener arrangements act efficiently in conjunction with their cooperative parts to maintain the hood in fixed relation to the respirator and to retain the window or eye band securely in place. The entire device is extremely light in weight, neat in appearance and comfortable in use and when not in use may be folded so as to occupy a minimum of space.

However it is to be understood that several changes or modifications may be made and that although the construction of the respirator is herein described as having a face piece 12 provided with forwardly projection inhalation means and depending exhalation means, the hood may be used with several different types of respirators. It is also to be understood that although the description hereinbefore refers to a head band attached to the sides of the respirator face piece and extending around the head of the wearer, the head band may be of any of the known used commercial types connected by suitable means to secure the respirator to the wearer's head. The snap fastener arrangements shown are merely illustrative of one convenient means of securing the straps 46, free edges of frontal portions 28 and 29, and flap 40, but it is

to be understood that other suitable mechanical means may be employed.

Also, although the description of the hood refers mainly to the parts thereof as being connected together by stitching it is to be understood that other means may be employed for this purpose such as by the use of adhesives.

It will be apparent that any changes and modifications may be made in the details of construction and arrangement of parts shown and described without departing from the spirit of the invention as expressed in the accompanying claims. Therefore, it is to be understood that all matter set forth or shown in the accompanying drawings is to be interpreted as illustrative and not in a limiting sense.

Having described my invention, I claim:

1. A protective covering for the head comprising a hood having a cap portion with a forwardly projecting visor, a drape portion secured to and depending from the cap portion and peripheral edge of the visor, and a window located in the front of said drape portion comprising a bezel fixedly secured in said drape portion beneath said visor, said peripheral edge embodying a channeled portion for receiving the adjacent edge of a transparent member and having a portion of its peripheral margin open for the insertion of said transparent member, and a flap member adapted to seal the marginal opening in the bezel.
2. A protective covering for the head comprising a hood having a cap portion with a forwardly projecting visor, an elastic band member provided in the cap portion to adjust the cap portion to the head of the wearer, a drape portion secured to and depending from the cap portion and peripheral edge of the visor, and a window located in the front of said drape portion comprising a bezel fixedly secured in said drape portion beneath said visor, said bezel embodying a channeled portion for receiving the edge of a transparent member and having its upper peripheral margin open for the insertion of said transparent member, and a flap member secured to the forward edge of said visor and having means for connection with the upper marginal portion of the bezel to seal the opening in said marginal portion of the bezel.
3. A protective covering for the head comprising a hood having a cap portion adapted to be supported on the head of the wearer, a visor portion secured to the front of said cap portion and having stiffening means associated therewith, an elastic band member provided in the cap portion to adjust the cap portion to the head of the wearer, a drape portion secured to and depending from the cap portion and edge of the visor, and a window located in the front of said drape portion comprising a bezel fixedly secured in said drape portion beneath said visor, said bezel having a portion of its peripheral margin open for the insertion of a transparent member, and a flap member carried by the drape portion for connection with the marginal portion of the bezel to seal the marginal opening in the bezel.
4. A head protecting hood comprising a cap portion having a visor, a drape portion attached to and depending from the lower edges of said cap portion and visor, a window located in the front of said drape portion beneath the visor, and means for attachment of the hood to a respirator consisting of an opening formed in the drape portion through which portions of the respirator

may project, the opening having convergent strap members formed on the opposed sides thereof, the strap members being adapted to be drawn into lapping relation adjacent the projecting portions of the respirator to secure the hood to the respirator.

5. A head protecting hood for use with respirators comprising a cap portion adapted to be supported upon the head of the wearer, a visor portion formed integral with said cap portion and having stiffening means associated therewith, a drape portion depending from said cap and visor portions and having a window located in the front thereof, and means for attachment of the hood to a respirator consisting of an opening formed in the drape portion through which portions of the respirator may project, the opening having convergent strap members formed on the opposed sides thereof, the strap members being adapted to be drawn into lapping relation adjacent the projecting portion of the respirator to secure the hood to the respirator.

6. A head protecting hood for use with respirators comprising a cap portion adapted to be supported upon the head of the wearer, a visor portion formed integral with said cap portion and having stiffening means associated therewith, an elastic band member provided in the cap portion to adjust the cap portion to the head of the wearer, a drape portion depending from said cap and visor portions and having a window located in the front thereof, and means for attachment of the hood to a respirator consisting of an opening formed in the drape portion through which portions of the respirator may project, the opening having convergent strap members formed on the opposed sides thereof, the strap members being adapted to be drawn into lapping relation adjacent the projecting portions of the respirator to secure the hood to the respirator.

7. A protecting hood adapted to cover the head of a wearer and having an opening formed in the front thereof, a bezel bordering the opening and having a marginal portion thereof open for insertion of a transparent member, a flap member adapted to cover the open portion of said bezel, a second opening beneath the first opening for reception of a portion of a respiratory device to which the hood is to be attached, and straps formed on the opposed sides of said second opening for attachment of the hood to said device.

8. In a combined hood and respirator, a face piece adapted to fit snugly over the face of the wearer and carrying spaced inhalation and exhalation means, and a cap member adjustably supported upon the head of the wearer and having a visor and a drape member, the drape member covering entirely the head of the wearer and having a window located in the front thereof beneath said visor, an opening being provided in the front of the drape member beneath said window for projection of said exhalation and inhalation means, the opening having convergent strap members formed on the opposed sides thereof and adapted to be drawn together between the exhalation and inhalation means to secure the hood to the respirator.

9. In a combined hood and respirator, the combination of a face piece adapted to fit snugly over the nose and mouth of the wearer, inhalation means located on the front of the face piece, exhalation means located on the face piece in the lower regions thereof, a cap member adapted to be supported upon the head of the wearer and

having a forwardly projecting visor, an elastic band member provided in the cap member to adjust the hood to the head of the wearer, a drape portion depending from said cap and visor over the entire head of the wearer and covering a major portion of the respirator and having means for securing the drape portion beneath the arms of the wearer, a removable window located in the front of the drape portion beneath said visor, and means for attaching the hood to the respirator comprising an opening formed in the drape portion beneath the window through which the said inhalation and exhalation means may project, the opening having convergent strap members formed on the opposed sides thereof, the strap members being adapted to be drawn into lapping relation between the exhalation and inhalation means to secure the hood to the respirator.

10. A combined head protecting hood and respirator comprising a cap portion, a drape portion depending from said cap portion, a window opening located in the front of said drape portion beneath the cap portion, a window in said opening, a respirator opening formed in the drape portion beneath the window opening and through which a portion of a respirator may extend, said portion of the drape having the respirator opening therein having strap members formed adjacent the lower sides of said opening, said strap members being adapted to be secured in overlapping relation with each other beneath the portion of the respirator which extends through the respirator opening to secure the hood to said respirator.

11. A head protecting hood for use with respirators comprising a cap portion adapted to be supported upon the head of the wearer, a drape portion depending from said cap portion and having a window opening located in the front thereof, a window of transparent flexible sheet material in said window opening, and means for attachment of the hood to a respirator consisting of a second opening formed in the drape portion beneath the window opening and through which a portion of the respirator may project, said second opening having strap members formed adjacent the lower side edges thereof, said strap members being adapted to be secured in overlapping relation beneath the projecting portion of the respirator when assembled therewith to secure the hood to the respirator and being adapted to cause the flexible window to cup outwardly for clearance with the face of the wearer.

12. In a combined hood and respirator, a face piece adapted to fit snugly over the face of the wearer and carrying spaced inhalation and exhalation means, and a cap member adjustably supported upon the head of the wearer and having a drape member extending downwardly thereof, the drape member covering entirely the head of the wearer and having a window opening therein, a window in said window opening, and a second opening in said drape member beneath said window opening for projection of said exhalation and inhalation means therethrough, said second opening having convergent strap members formed on the opposed lower sides thereof and adapted to be drawn and secured together between the exhalation and inhalation means to secure the hood to the respirator.

13. In a combined hood and respirator, the combination of a face piece adapted to fit snugly over the nose and mouth of the wearer, inhala-

tion means located on the front of the face piece, exhalation means located on the face piece in the lower regions thereof, a cap member adapted to be supported upon the head of the wearer, adjustable means in the cap member to adjust the hood to the head of the wearer, a drape portion depending from said cap over the entire head of the wearer and covering a major portion of the shoulders and having means extending beneath the arms of the wearer to secure the drape portion to the shoulders, a window opening in the drape portion, a removable window located in the window opening, and means for attaching the hood to the respirator comprising a second opening beneath the window opening and through which the said inhalation and exhalation means may project, said second opening having convergent strap members formed on the opposed lower sides thereof and being adapted to be drawn and secured together between the exhalation and inhalation means to secure the hood to the respirator.

14. A protecting hood adapted to cover the entire head of the wearer and having an opening formed in the front thereof, a channelled portion bordering the opening and having a portion thereof open for the insertion of a transparent member, means adapted to cover the

open portion of said channelled portion to removably secure the transparent member therein, and a second opening beneath the first opening for the reception of a respiratory device to which the hood may be attached, and convergent straps formed on the opposed sides of said second opening for attachment of the hood to said device.

GEORGE H. SCHAUWEKER.
